UNITED STATES PATENT OFFICE.

WALDO E. ROSEBUSH, OF APPLETON, WISCONSIN.

FIREARM.

1,311,715.

Specification of Letters Patent. Patented July 29, 1919.

Application filed November 19, 1917. Serial No. 202,747.

To all whom it may concern:

Be it known that I, WALDO E. ROSEBUSH, a citizen of the United States, and a resident of Appleton, in the county of Outagamie and State of Wisconsin, have invented a new and Improved Firearm, of which the following is a full, clear, and exact description.

The invention relates to recoil operated breech loading hand firearms, such as shown and described, for instance, in the application for Letters Patent of the United States, Serial No. 117,660, filed by me on August 30, 1916.

15 The object of the invention is to provide a new and improved firearm arranged to permit of securely locking the barrel receiver to the main frame and to allow convenient disassembling of the said parts for repairs, 20 cleaning or other purposes. Another object is to force the breech block back automatically when disassembling the parts to cause the extractor to clear the barrel and thereby permit removal of the barrel from the receiver without completely disengaging the barrel receiver from the main frame. Another object is to cause the hammer spring to act on the magazine catch. Another object is to permit of adapting the magazine 30 to long rifle cartridges as well as to short cartridges and without danger of the bullets jamming in the magazine. Another object is to securely hold the wooden handles in position on the handle portion of the main 35 frame by simple, efficient, interior means. Other objects will readily appear from the detailed description of the firearm.

A practical embodiment of the invention is represented in the accompanying drawings 40 forming a part of this specification, in which similar characters of reference indicate corresponding parts in all the views.

Figure 1 is a side elevation of the firearm;

45 Fig. 2 is a plan view of the same;

Fig. 3 is a side elevation of a portion of the firearm with parts in section and with parts partly disassembled;

50 Fig. 3^a is a similar view of the same with the parts in a further disassembled position;

Fig. 4 is a longitudinal central section of the firearm with some of the parts shown in elevation;

55 Fig. 5 is a similar view of the same with the breech block in recoil position;

Fig. 6 is a sectional plan view of the same on the line 6—6 of Fig 4;

Fig. 7 is a perspective view of the breech block;

Fig. 8 is a similar view of the barrel receiver;

Fig. 9 is a similar view of the main frame;

Fig. 10 is a perspective view of the back strap;

Fig. 11 is a similar view of the extractor with the parts in disassembled position except the spring;

Fig. 12 is a perspective view of the firing pin;

Fig. 13 is a similar view of the bearing for the firing pin;

Fig. 14 is a cross section of the firearm on the line 14—14 of Fig. 4;

Fig. 15 is a similar view of the same with the barrel in unlocked position ready for removal from the barrel receiver;

Fig. 16 is a perspective view of the barrel;

Fig. 17 is a perspective view of the locking device for the magazine;

Fig. 18 is a perspective view of the locking lever for locking the breech block in recoil position after the last cartridge has been fired;

Fig. 19 is a perspective view of the controlling piece for the sear;

Fig. 20 is a perspective view of the sear;

Fig. 21 is a similar view of the trigger;

Fig. 22 is a like view of the hammer;

Fig. 23 is a side elevation of the magazine;

Fig. 24 is a perspective view of the magazine follower;

Fig. 25 is a plan view of the magazine;

Fig. 26 is a sectional plan view of the same on the line 26—26 of Fig. 23;

Fig. 27 is a cross section of the same on the line 27—27 of Fig. 23 and showing the cartridge in position in the magazine;

Fig. 28 is a cross section of the magazine on the line 28—28 of Fig. 23;

Fig. 29 is a cross section of the wooden handle, locked in place at its upper end on the main frame by the barrel receiver, the section being on the line 29—29 of Fig. 1; and

Fig. 30 is a similar view of the lower end of the said wooden handle in position on the handle part of the main frame.

The main frame 40 of the firearm is provided with a suitable handle 41 and a trigger

guard 42, as plainly shown in Fig. 9. The forward end of the main frame 40 is provided with integral half round pivots 43 adapted to be engaged by correspondingly shaped notches 44 formed in the sides 45 of a barrel receiver 46 (see Figs. 1, 3* and 8) to permit of swinging the said barrel receiver 46 into and out of position on the main frame 40 when assembling or disassembling 10 the firearm. The sides 45 fit snugly over the sides of the main frame 40 so as to hold the parts mounted on the said frame against accidental displacement. The barrel receiver 46 is provided with a central bore 47 into 15 which fits the reduced rear end 48 of the barrel 49 provided with a shoulder 50 abutting against the forward end of the barrel receiver 46, as plainly indicated in the drawings. The reduced portion 48 of the barrel 20 49 is provided on the top and bottom with two sets of spaced lugs 51 and 52 adapted to pass through longitudinal recesses 53 formed in the side walls of the bore 47 of the barrel receiver 46, and the said lugs 51 and 25 52 are adapted to register with transverse recesses 54 and 55 formed in the top and bottom of the wall of the bore 47. In placing the barrel 49 in position on the barrel receiver 46 so that the lugs 51 and 52 are made to register with the longitudinal 30 recesses 53 to permit of passing the reduced portion 48 of the barrel into the bore 47 until the shoulder 50 abuts against the forward end of the barrel receiver 46 and the lugs 51 and 52 are in register with the recesses 54 and 55. A quarter turn is now given to the barrel so that the lugs 51 and 52 pass into the recesses 54 and 55 thus locking the barrel against longitudinal displacement. 35 40 45 50 55 60 65 70 75 80 85 90 95 100 105 110 115 120 125

ment in the barrel receiver 46 (see for comparison Figs. 14 and 15). The rear end of the reduced portion 48 of the barrel 49 is flush with the rear end of the barrel receiver 46, and is provided at the bottom with a beveled lug 60 fitting into a notch 61 formed in the top of a lug 62 which is an integral part of the main frame 40, as plainly shown in Fig. 9. The back of the lug 62 is beveled to correspond to the bevel of the lug 60 to guide a cartridge into the bore 63 of the barrel, as hereinafter more fully explained. It will also be noticed that by the lug 60 engaging the notch 61 the barrel 49 is held against accidental turning when the parts are assembled and the firearm is in use.

On the upper edges of the rear portions of the sides 45 of the barrel receiver 46 is mounted to slide forward and backward a breech block 70 provided with a forward extension in the form of two side bars 71 and 72 (see Fig. 7) connected with each other at their forward end by a crossbar 73. The lug 62 of the main frame 40 previously mentioned fits between the side bars 71 and 72

and thus aids in guiding the breech block 70 in its forward and backward sliding movement. The under side of the breech block 70 is provided with a longitudinally extending tongue 74 mounted to slide on a guideway 75 formed on the top of a lug 76 integral with the main frame 40 at the rear end thereof (see for comparison Figs. 7 and 9). The forward end of the tongue 74 is adapted to engage and push a cartridge into the barrel 49, as hereinafter more fully explained. The forward end of the left-hand side of the guideway 75 forms an ejector 77 adapted to be engaged by the rim of an empty shell extracted from the barrel to insure a sidewise deflection of said shell to the right on the recoil action of the breech block 70, as hereinafter described.

The breech block 70 is held normally in a forward position by the action of a breech block spring 80 extending with its forward portion into a tube 81 which forms an extension of the crossbar 73 previously mentioned, and the forward end of the spring 80 abuts against the forward end 82 of the tube 81. The rear end of the spring 80 bears against a nut 83 held between the side bars 71 and 72 to prevent the nut from turning but to allow the nut to slide between the said side bars 71 and 72. The nut 83 screws on the rear portion of a locking and guide rod 84 around which the spring 80 is coiled, and the guide rod extends with its forward end through the forward end 82 of the tube 81. The forward end of the locking rod 84 terminates in a handle 85. By the arrangement described a long breech block spring may be used and the tension thereof adjusted by turning the rod to screw the nut 83 forward or backward between the side bars 71 and 72. The rear end of the locking rod 84 extends through a depending lug 86 integral with the under side of the barrel receiver 46 and abutting against the front of the abutment lug 62 of the main frame 40. The rear terminal of the locking rod 84 extends into a recess 87 formed in the lug 62 of the main frame 40. Thus by the arrangement described the rod 84 forms a guide for the breech block 70 and also forms a locking device for locking the barrel receiver 46 in position on the main frame 40, that is, to prevent the barrel receiver 46 from swinging upward on the main frame 40. In order to unlock the barrel receiver 46 it is necessary for the operator to pull forwardly on the handle 85 of the rod 84 to disengage the rear end thereof from the recess 87 in the lug 62.

When it is desired to push the breech block 70 rearwardly by hand for loading the firearm by hand or for other purposes then the operator takes hold of the roughened sides of the breech block 70 and pushes the same rearwardly against the tension of the

spring 80. The tube 81 projects through a recess or notch 88 formed between two lugs 89 integral with the forward end of the main frame 40 and carrying the pivots 43 previously mentioned. The bottom of the notch 88 is rounded off in a downward direction (see Figs. 3, 4 and 5) to permit a slight tilting of the breech block 70 as indicated in Fig. 3* and to prevent denting or binding of the tube 81 and pinching of the recoil spring 80 while disassembling the firearm. The forward face of the crossbar 73 of the breech block 70 normally abuts against the backs of the lugs 89 and hence when the barrel receiver 46 is tilted upwardly then a slight rearward movement is automatically given to the breech block 70 for the purpose hereinafter more fully explained (see Fig. 3*).

The rear ends of the sides 45 of the barrel receiver 46 are locked in place by the use of a back strap 100 fitting into a recess in the back of the handle 41 of the main frame 40. The lower end of the strap 100 is pivoted at 101 to the handle 41 and the upper end of the said back strap 100 is provided with forwardly extending lugs 102 (see Figs. 3, 4, 5 and 10) fitting the sides of the main frame 40 and terminating in catches 103 engaging shoulders 104 formed on the rear edges of the sides 45 of the barrel receiver 46 thus holding the barrel receiver locked in position at its rear end. The back strap 100 is provided with a recess 105 in which is arranged a hammer spring 106 pressing with its upper end on the under side of a plunger or head 107 mounted to slide in the recess 105. The top of the plunger 107 is provided with a concave recess 108 engaged by the lower end of a link 109 pivotally connected at its upper end at 110 to the heel 111 of the hammer 112 mounted to swing on the pivot 113 mounted on the main frame 40. The hammer 112 is adapted to engage the firing pin 114 mounted to slide in the breech block 70 to fire the cartridge 115 held in the rear end of the barrel 49 at the time. The bottoms of the lugs 102 of the back strap 100 normally rest on lugs 116 formed integral with the sides of the main frame 40, as plainly indicated in the drawings. The lower end of the hammer spring 106 bears on an arm 120 projecting at an angle from a catch 121 provided with trunnions 122 (see Figs. 4 and 17) mounted to turn in the back strap 100. The catch 121 extends downward through the handle 41 and its lower end is provided with a plate 123 adapted to engage the under side of the bottom 124 of a magazine 125 removably held in the handle 41. By the arrangement described the hammer spring 106 controls the hammer 112, the catch 121 and the back strap 100 owing to the fact that the catch 121 is pivoted on the back strap, as will be

readily understood by reference to Fig. 4. The back strap 100 is provided with a rearwardly extending fingerpiece 126 to permit of conveniently swinging the back strap 100 rearwardly against the tension of the spring 106 whenever it is desired to disengage the catches 103 from the shoulders 104. The fingerpiece 126 is also adapted to be engaged by the fingerpiece 127 of the hammer 112 to lock the back strap 100 in its normal forward position when the hammer 112 is cocked, thus preventing disassembling of the firearm while the hammer 112 is in cocked position (see Fig. 5). It will also be noticed that the frame 40 and the barrel receiver 46 are locked together when the hammer 112 is cocked as the hammer 112 cannot be completely cocked if the back strap 100 is not in its normal forward position. When the barrel receiver 46 is in locked position the tops of the lugs 102 of the back strap 100 fit against the under side of the breech block 70 thus preventing a rearward swinging movement of the back strap 100. It will be noticed that by this arrangement the back strap 100 cannot be swung rearwardly as long as the firearm is used and the breech block 70 is in normal position, but when the firearm is to be disassembled, the operator first presses the fingerpiece 126 and thereby swings the back strap 100 rearwardly to disengage the catches 103 from the shoulders 104 (see Fig. 4) and then the breech block is slightly swung upward, as previously explained. The operator can now swing the barrel receiver 46 farther upward into the position shown in Fig. 3*, after which the barrel 49 can be removed from the barrel receiver 46 in the manner previously explained.

The firing pin 114 has its forward end mounted to slide in a bearing 130 formed in the forward end of the breech block 70, and the firing pin extends through a bore 131 formed in the breech block 70, as plainly shown in Fig. 4. The firing pin 114 is provided adjacent its rear end 132 with a collar 133 against which abuts the rear end of the firing pin spring 134 resting with its forward end on the forward wall of the bore 131. The rear end 132 of the firing pin 114 is mounted to slide in a bearing 135 provided with a flat base 136 (see Figs. 4 and 13) engaged at the top by a flat bottom portion 137 (see Figs. 4 and 12) of the collar 133 to hold the firing pin 114 against turning. The bearing 135 is inserted into the bore 131 through an aperture 138 formed in the bottom of the breech block 70. The terminal of the rear end 132 of the firing pin 114 projects a short distance beyond the rear face of the breech block 70 for engagement by the hammer 112 when the firearm is fired.

The breech block 70 is provided at its right hand side (see Fig. 6) with a bore 13

150 in the forward end of which is arranged the extractor 151 having its hook 152 projecting beyond the forward end of the breech block 70 to pass into a recess 153 formed in the rear end of the reduced portion 48 of the barrel 49 with a view to engage the rim of the cartridge 115 in position at the time in the rear end of the barrel. The extractor 151 is provided with an angular pivot portion 154 extending into a recess 155 formed in the wall of the bore 150 to allow the extractor 151 to swing in order to pass over the rim of the cartridge 115 during the return stroke of the breech block 70. The heel of the extractor 151 is engaged by a shoulder 156 formed on a plunger or head 157 mounted to slide in the bore 150 and pressed on by a spring 158 held in the rear end of the said bore. By the arrangement described, the extractor 151 is spring pressed to firmly engage its hook 152 with the rim of the cartridge 115. The plunger or head 157 is provided with a rearwardly extending pin 159 extending into the opening of the spring 158 to hold the latter in proper centered position. The extractor 151 can be readily removed from the bore 150 by first pressing the plunger 157 rearwardly in the bore and against the tension of its spring 158 to allow of lifting the pivot 154 out of the recess 155 and then allow of withdrawing the extractor 151 through the forward end of the bore 150. The plunger 157 and the spring 158 can then also be removed from the bore.

The sear 170 in construction and action is practically the same as the one shown and described in the application for Letters Patent above referred to so that further detailed description of the same is not deemed necessary, it being understood, however, that the forward end of the sear 170 is pressed on by a spring 171 to normally hold the sear 170 in rearmost position to engage the hammer 112 and to hold the same in cocked position. The spring 171 is mounted on a pin 172 provided with a head 173 having a transverse knife edge bearing on the front wall of a slot 175 formed in the main frame 41. The knife edge 174 allows a free up and down rocking movement of the sear 170. The rear end of the sear 170 (see Fig. 4) is provided with a rounded off pivot 176 extending loosely into a transverse bearing 177 formed in the main frame 41 to allow the sear to rock up and down and also to allow forward and rearward movement of the said sear. The rear pivotal end 176 of the sear 170 is provided with a tooth 178 adapted to engage a shoulder or notch 179 on the heel 111 of the hammer 112 to hold the latter in cocked position. The sear 170 is provided near its forward end with a square shoulder 180 adapted to be engaged by a projection 181 formed on the trigger 182 fulcrumed at 183 in the main frame 40.

The trigger 182 is provided with a finger-piece 184 extending into the trigger guard 42 to be in convenient position for the operator's finger for pressing the trigger whenever it is desired to move the sear 170 forward against the tension of the spring 171 to release the hammer 112 for firing purposes.

In order to prevent the firearm from being fired except when the breech block is completely and tightly closed, the following arrangement is made: On the top of the sear 170 in the front of the shoulder 180 is arranged a controlling safety piece 200 (see Fig. 19) of U-shape and having its arms 201 mounted to slide in recesses 202 formed in the sides of the main frame 41 (see Fig. 9). The upper blunted off ends of the arms 201 are adapted to engage notches 203 formed in the under side of the side bars 71 and 72 of the breech block 70 (see Fig. 7). When the breech block 70 moves rearwardly then the notches 203 pass out of engagement with the arms 201 and the bottoms of the side bars 71 and 72 now press the controlling piece 200 downward and with it the sear 170 rocking on the bearing 176.

It is understood that the breech block 70 moves rearwardly on the recoil action of the fired gun (see Fig. 5) and in doing so the rear end of the breech block 70 imparts a rearward swinging movement to the hammer 112 whereby the hammer is cocked and held in position by the sear 170 while the breech block 70 immediately returns to its forward position by the action of the spring 80. When the operator presses the finger-piece 184 of the trigger 182 then the sear 170 releases the hammer 112 which swings forward by the action of its spring 106 to cause the firing pin 114 to fire the cartridge 115 in the barrel 49. The sear 170 is forced rearward by the spring 171 as soon as the pressure on the rear end of the sear 170 is relieved by the release of the hammer 112.

The magazine 125 (see Figs. 4 and 23 to 28, inclusive) is removably held in the handle 41 and is adapted to hold short and long cartridges 115, say 22 caliber, as illustrated in Fig. 27, or the magazine is adapted to hold the regular 32 caliber rimless automatic cartridges now generally used in the ordinary automatic firearm. For the purpose mentioned, the magazine 125 is provided in its rear portion with a filling piece 210 extending from the bottom 124 to the top of the magazine 125 to narrow the available space within the magazine for short cartridges 115, as will be readily understood by reference to Fig. 4. For longer cartridges this filling piece 210 is removed from the magazine to provide additional space for the increased length of such cartridges. To accommodate 32 caliber cartridges, the magazine is provided with straight sides in

stead of the inwardly bent sides shown in Fig. 26. It is understood that when using cartridges of different calibers it is necessary to use barrels 49 with correspondingly rigid bores 63. The cartridges 115 are forced upward in the magazine 125 by a follower 212 pressed on by a spring 213 resting with its lower end on a guide 214 seated in a seat 215 formed in the upper face of the bottom 124. The guide 214 serves as a locking means to hold the bottom 124 against accidentally sliding out of the lower end of the magazine, and when it is desired to remove the slidible bottom 124 it is necessary first to unseat the guide 214 from its seat 215 by the use of a suitable tool introduced through an aperture 216 formed in the bottom 124 and leading to the seat 215. The bottom 124 is provided at the sides with guideways 220 engaged by inwardly pressed lugs 221 on the lower end of the magazine 125 (see Figs. 23 and 28). The follower 212 is provided with a fingerpiece 225 projecting through slots 226 formed in the magazine 125, and the fingerpiece 225 projects into the path of a transverse lug 227 (see Figs. 18 and 26), formed on the rear end of a lever 228 pivoted at 229 on the main frame 40. The lever 228 is provided with a fingerpiece 230 which extends into the top of the trigger guard 42 to be within convenient reach of the operator, and a spring 231 (see Fig. 4) is interposed between the trigger 182 and the lever 228 to render both the trigger and the lever spring pressed with a view to cause the same to return to normal positions after being first pressed and then released. The rear end of the lever 228 is provided with a lug 232 adapted to engage a recess 239 formed in the under side of the side bar 71 (see Fig. 7) to hold the breech block 70 in recoil position after the last cartridge is fired owing to the action of the fingerpiece 225 on the lug 227 and which action causes an upward swinging movement of the lever 228 to cause its lug 232 to engage the recess or notch 239 at the time the breech block 70 reaches a recoil position after the last cartridge is fired. It is understood that when the last cartridge leaves the magazine 125 the follower 212 moves into uppermost position and with it its fingerpiece 225 whereby the latter engages the lug 227 and swings the lever 228 upward against the tension of the spring 231.

The upper ends of the rear portions of the sides of the magazine are bent inwardly to form retaining lips to guide the uppermost cartridge when pushed forwardly by the returning breech block 70. The upper forward portions of the sides of the magazine 125 are provided with resilient centering lips 241 extending inwardly (see Fig. 25) to hold the uppermost cartridge properly centered relatively to the bore 63 of the

barrel 49 at the time of pushing this uppermost cartridge 115 into the said barrel bore.

The fingerpiece 225 is also used to push the follower 212 downward to permit of loading the magazine with cartridges from the top, it being only necessary to drop the cartridges one by one into the magazine while pushing the follower correspondingly downward.

The handle 41 is provided on each side with a wooden grip 250 provided on its inner face with an integral offset portion 251 fitting into an opening 252 (see Figs. 9, 29 and 30) formed in the handle 41. The offset portion 251 projects at its upper end beyond the top of the face of the grip 250, and this top portion 253 extends under the lower rear portion of the corresponding side 45 of the barrel receiver 46. The lower edge 254 of the offset portion 251 is beveled and fits on a corresponding bevel 255 formed on the bottom wall of the opening 252 of the handle 41. When assembling the parts the hand grips 250 are engaged at their lower beveled edge 254 with the bevels 255, and when the barrel receiver 46 is swung into final position its sides 45 overlie the tops 253 of the grips 250 thus securely locking the said handle grips in place without the use of screws or other similar fastening device. The forward end of the barrel 49 is provided at the top with a suitable front sight 260, and a rear sight 261 is arranged on the top of the breech block 70.

The operation is as follows:

When the several parts are in the position shown in Figs. 1, 2, 4 and 6 with the magazine 125 filled with cartridges and one being in the breech of the barrel, then the operator first moves the hammer 112 into cocked position and then presses the fingerpiece 184 of the trigger 182 to move the sear 170 forward and thereby release the hammer 112 which by the spring mechanism is caused to swing forward and strike the firing pin 114 to fire the cartridge. When this takes place the breech block 70 recoils and in doing so swings the hammer 112 back into cocked position. The empty shell moves rearward out of the barrel by the recoil of the exploded shell aided by the extractor 151, and when the rim of the empty shell strikes the ejector 77 it is deflected to the right and is thrown sidewise out of the space between the rear end of the barrel and the forward end of the breech block 70, as will be readily understood by reference to Fig. 5. During the return or forward movement of the breech block 70 the rim of the uppermost cartridge in the magazine 125 is engaged by the tongue 74 of the forward end of the breech block 70 whereby the uppermost cartridge is pushed forwardly out of the throat and from between the lips 241 of the magazine, and the cartridge is then pushed

100

105

110

115

120

125

130

forward into the bore 63 of the barrel 49. It is understood that the breech block 70 is returned to its normal foremost position by the action of its spring 80. On pressing the 5 fingerpiece 184 of the trigger 182 a second time, the cocked hammer 112 is released and a second shot is fired, and then the above described operation is repeated except that it is not necessary for the operator to cock 10 the hammer 112 as this is done by the breech block 70. When the last cartridge in the magazine 125 has been pushed out of the magazine and pushed into the barrel by the returning breech block 70, then the fingerpiece 225, presses on the lug 227 and after 15 this last cartridge is fired and the breech block 70 is moved rearward, then the lug 232 of the lever 228 engages the notch 233 thus locking the breech block 70 in rearmost position thereby indicating to the user 20 of the firearm that the last cartridge has been fired. The magazine 125 may then be removed and refilled with cartridges and again reinserted in the handle. The breech block 70 can be readily unlocked on the operator pressing the fingerpiece 230 of the lever 228 to disengage the lug 232 thus unlocking the breech block 70 and allowing the same to return to normal forward position 25 by the action of its spring 80. It is understood that when the breech block 70 is in the locked position shown in Fig. 5 a cartridge can be pushed into the rear end of the bore 63 by hand, if it is desired, to do so.

30 When it is desired to disassemble the firearm, the operator first presses the fingerpiece 125 to swing the back strap 100 rearwardly and thus disengage the catches 103 from the shoulders 104 and swing the breech block 40 70 slightly upwardly, as indicated in Fig. 3, after which the operator withdraws the rod 84 from the recess 87 of the lug 62. A swinging movement can now be given to the barrel receiver 46, turning on the pivots 43 and in doing so the forward end of the 45 cross bar 73 of the breech block 70 travels up on the rear face of the lug 89 whereby the breech block 70 is pushed slightly rearwardly (see Fig. 3^a) for the rear end of the barrel to clear the extractor 151 and for the lug 60 to disengage the notch 61 in the lug 60 of the main frame 41 to allow turning of the barrel 49 in the barrel receiver 46. The barrel 49 can now be removed 50 from the barrel receiver 46 by giving the barrel a quarter turn to disengage the lugs 51 and 52 from the recesses 54 and to move the said lugs into the recesses 53 to permit the reduced end 48 of the barrel to slide out of the bore 47 on pulling the barrel 49 in a forward direction. If desired, the barrel receiver 46, with the barrel 49 and the breech block 70 mounted thereon can be 55 completely disengaged from the frame 41 by 60 swinging the barrel receiver 46 into the po-

sition shown in Fig. 3^a and then pushing the same rearward and upward to disengage the pivots 43. Ready access is now had to the trigger mechanism, the sear 170 and the various other parts for removal and inspection of the same, if desired. The parts can be readily assembled in reverse order and the barrel receiver locked in place by the back strap 100, as above explained. When it is desired to remove the follower 212 and 70 the spring 213 from the magazine 125 the operator pulls out the bottom 124 after first displacing the guide 214, as previously explained, to permit of removing the spring and the follower by way of the lower end 75 of the magazine.

Having thus described my invention, I claim as new and desire to secure by Letters Patent:

1. In a hand firearm, the combination of a 85 barrel, a barrel receiver in which the barrel is removably held, a main frame on which the forward end of the barrel receiver is mounted to swing, and a back strap mounted to swing on the main frame and engaging 90 the rear end of the said barrel receiver to lock the latter in place on the main frame.

2. In a hand firearm, the combination of a 95 barrel, a barrel receiver in which the barrel is removably held, a recoil operated breech block slideable on the said receiver and having a slight up and down swinging movement on the receiver, a main frame on which the forward end of the barrel receiver is mounted to swing, and a back strap mounted 100 to swing on the main frame and engaging the rear end of the said barrel receiver to lock the latter in place on the main frame.

3. In a hand firearm, the combination of a main frame provided with a pivoted back 105 strap having its free end terminating in an integral catch, and a barrel receiver mounted to swing on the said main frame and provided at its rear end with a keeper adapted to be engaged by the said catch to lock the 110 barrel receiver in place on the main frame.

4. In a hand firearm, the combination of a main frame having a front lug and a notched rear lug, a barrel receiver fulcrumed at its forward end on the said front lug 115 of the main frame and a barrel mounted to turn in the said barrel receiver and having a lug at its rear end normally engaging the said rear notched lug of the main frame to hold the barrel against turning in the barrel receiver unless the latter is swung into a tilted position.

5. In a hand firearm, the combination of a main frame, a barrel receiver fulcrumed at its forward end on the main frame, a back 125 strap pivoted on the rear end of the main frame, the rear end of the said barrel receiver and the free end of the said back strap having locking means to lock the barrel receiver to the main frame. 130

6. In a hand firearm, the combination of a main frame, a barrel receiver fulcrumed at its forward end on the main frame, a back strap pivoted on the rear end of the main frame, the rear end of the said barrel receiver and the free end of the said back strap having locking means to lock the barrel receiver to the main frame, and a spring pressing the said back strap to normally hold the back strap in locking position relative to the barrel receiver. 70
7. In a hand firearm, the combination of a main frame, a barrel receiver mounted to swing on the said main frame, a barrel mounted on the said barrel receiver, a recoil operated breech block slidable on the said barrel receiver and provided with a firing pin, a hammer pivoted on the main frame and adapted to engage the said firing pin, a spring pressing the said hammer, and a locking device held on the rear end of the said main frame and engaging the rear end of the said barrel receiver, the said locking device being pressed by the hammer spring. 80
8. In a hand firearm, the combination of a main frame, a barrel receiver mounted to swing on the said main frame, a barrel mounted on the said barrel receiver, a recoil operated breech block slidable on the said barrel receiver and provided with a firing pin, a hammer pivoted on the main frame and adapted to engage the said firing pin, a spring pressing the said hammer, a back strap fulcrumed at its lower end on the said main frame, the rear end of the said barrel receiver and the free end of the said back strap having locking means to lock the barrel receiver in position on the said main frame, the said hammer spring pressing the said back strap to hold the same in normal position. 90
9. In a hand firearm, the combination of a main frame, a barrel receiver mounted to swing on the said main frame, a barrel mounted on the said barrel receiver, a recoil operated breech block slidable on the said barrel receiver and provided with a firing pin, a hammer pivoted on the main frame and adapted to engage the said firing pin, a spring pressing the said hammer, a back strap fulcrumed at its lower end on the said main frame, the rear end of the said barrel receiver and the free end of the said back strap having locking means to lock the barrel receiver in position on the said main frame, the said hammer spring pressing the said back strap to hold the same in normal position, the said back strap having a rearwardly extending fingerpiece. 100
10. In a hand firearm, the combination of a main frame, a barrel receiver mounted to swing on the said main frame, a barrel mounted on the said barrel receiver, a recoil operated breech block slidable on the said barrel receiver and provided with a firing pin, a hammer pivoted on the main frame and adapted to engage the said firing pin, a spring pressing the said hammer, a back strap fulcrumed at its lower end on the said main frame, the rear end of the said barrel receiver and the free end of the said back strap having locking means to lock the barrel receiver in position on the said main frame, the said hammer spring pressing the said back strap to hold the same in normal position, the said back strap having a rearwardly extending fingerpiece. 110
11. In a hand firearm, the combination of a main frame, a hammer pivoted on the said main frame and having a fingerpiece, and a back strap having a fingerpiece and pivoted on the said main frame, the said fingerpiece of the hammer being adapted to engage the fingerpiece of the back strap to lock the back strap when the hammer is in cocked position. 115
12. In a hand firearm, the combination of a main frame, a hammer pivoted on the said main frame and having a fingerpiece, a back strap having a fingerpiece and pivoted on the said main frame, the said fingerpiece of the hammer being adapted to engage the fingerpiece of the back strap to lock the back strap when the hammer is in cocked position, and a spring common to both the said hammer and the said back strap. 120
13. In a hand firearm, the combination of a main frame provided with spaced lugs, of which the front lug is recessed and provided with a pivot, a barrel receiver mounted to swing on the said pivot, a breech block mounted to slide on the said barrel receiver and provided with a tube extending through the said recess in the front lug, a rod extending through the said tube and engaging the said rear lug, and a spring interposed between the tube and the barrel receiver. 125
14. In a hand firearm, the combination of a main frame provided with spaced lugs, of which the front lug is recessed and provided with a pivot, a barrel receiver mounted to swing on the said pivot, a breech block mounted to slide on the said barrel receiver and provided with a tube extending through the recess in the front lug, a rod extending through the said tube and engaging the said rear lug, a spring interposed between the tube and the barrel receiver, and a spring pressed back strap on the rear end of the said main frame and engaging the rear end of the said barrel receiver to lock the rear end in place on the main frame. 130
15. In a hand firearm, the combination of a main frame, a barrel receiver mounted on the said main frame, a breech block slidable

- on the said barrel receiver and having a locking member engaging the said frame, and a spring pressed back strap pivoted on the said main frame and engaging the rear 5 end of the said barrel receiver, the said locking member of the breech block and the said back strap locking the barrel receiver in position.
16. In a firearm, the combination of a main frame provided with a notched lug, a barrel having a lug engaging the notch in the said frame lug, a barrel receiver mounted to swing on the said main frame and in which the said barrel is mounted to turn, a recoil operated breech block mounted to slide on the said barrel receiver, and coacting means on the said frame and the said barrel receiver to slide the breech block automatically rearwardly on the barrel receiver 10 on tilting the latter upwardly to disengage the barrel lug from the frame lug and thereby allow turning of the barrel in the barrel receiver for removal of the barrel and while the barrel receiver is in tilted position on the main frame.
17. In a firearm, the combination of a main frame provided at its forward end with a lug and with a pivot, a barrel, a barrel receiver in which the barrel is removably mounted, a recoil operated breech block mounted to slide on the said barrel receiver and having a shoulder abutting against the said lug to slide the breech block automatically rearwardly on tilting the said barrel 15 receiver upwardly on the said pivot as the fulcrum, and an extractor mounted on the said breech block and normally extending into the rear end of the barrel, the said extractor being free of the barrel at the time the barrel receiver is in the aforesaid tilted and rearward position to allow of removing the barrel from the barrel receiver while the latter is in tilted position on the main frame.
18. In a firearm, the combination of a main frame, a barrel, a barrel receiver
- mounted to swing on the said main frame and in which the barrel is removably mounted, a recoil operated breech block mounted to slide on the said barrel receiver, 50 an extractor mounted on the said breech block and normally extending into the rear end of the barrel, and coacting means on the said frame and the barrel receiver to slide the breech block automatically rearwardly 55 on tilting the said barrel receiver upwardly to free the extractor of the barrel to allow removal of the barrel from the barrel receiver while the latter is in tilted position on the main frame.
19. In a firearm, the combination of a frame having a handle portion, a barrel, a barrel receiver held on the said main frame and carrying the barrel, a recoil operated breech block slideable on the said barrel receiver and provided with a firing pin, a hammer pivoted on the frame and adapted to engage the said firing pin, a hammer spring pressing the said hammer, a magazine held in the said handle portion, a locking device for the said magazine and pressed by the said hammer spring, and a back strap pivoted on the said main frame and locking the said barrel receiver to the said main frame, the said back strap being pressed by 60 the said hammer spring.
20. In a firearm, the combination of a main frame having a handle portion provided with a transverse opening, the bottom wall of which is beveled inwardly and downwardly, a barrel receiver removably held on the said main frame and having side members, and hand grips overlying the said handle portion and each provided at its inner face with an integral boss fitting into the said opening, the upper end of the boss projecting beyond the top of the grip and under the corresponding side member of the barrel receiver, the lower edge of the boss being beveled to fit the said beveled 65 bottom.

WALDO E. ROSEBUSH.
